RESISTANCE SWITCH

William E. Baker, Chickasha, Okla., assignor of twenty-six and two-thirds per cent to Wiley True, twenty-six and two-thirds per cent to Roy I. Edwards, ten per cent to Randall H. Sharpe, and ten per cent to W. B. Jones and Edward B. Jordan

Original application February 4, 1949, Serial No. 74,582. Divided and this application August 31, 1949, Serial No. 113,390

6 Claims. (Cl. 201—48)

1

This invention relates to a resistance switch and the present application constitutes a division from by copending application filed February 4, 1949, Ser. No. 74,582.

One object of the invention is to provide a switch adapted for carrying high voltage and including in its construction a resistance which is gradually brought into and gradually engaged by a movable contact as the switch is closed.

Another object of the invention is to provide a switch wherein a block carrying the resistance and a stationary contact is tiltably mounted in a housing or casing and also carries a movable contact which is gradually moved into and out of engagement with the resistance during tilting movement of the block.

Another object of the invention is to provide a switch of this character wherein the block is yieldably held in a tilted position effecting complete engagement of the movable contact with the resistance, the block being tilted to a position moving the contact out of engagement with the resistance by a solenoid which is mounted in the casing or switch box and rests upon the bottom of the box.

Another object of the invention is to provide the switch with a casing or box having a closure at its front which is movable to opened and closed positions and formed with an opening through which a pin carried by the core of the solenoid projects so that the core may be manually moved to effect opening of the switch, there being a latch provided for engaging the pin and releasably holding the switch opened.

Another object of the invention is to provide a switch having a spring for tilting the block to a closed position so mounted that adjustments may be made to regulate tension of the spring.

With these and other objects in view the invention consists of a special construction and arrangement of parts illustrated in the accompanying drawings wherein:

Fig. 1 is a view showing the switch box in vertical section and mechanism within the box in side elevation.

Fig. 2 is a transverse sectional view taken along the line 2—2 of Figure 1.

Fig. 3 is a fragmentary view showing portions of the contact and resistance members in front elevation.

Fig. 4 is a view showing a portion of the switch box in vertical section at right angles to Figure 1 and the movable contact and the block carrying the stationary contact and the resistance in

2

front elevation with a portion of the movable contact broken away.

Fig. 5 is a sectional view taken vertically through Figure 4.

Fig. 6 is a front elevation showing the resistance coils and the carrier for the same.

Fig. 7 is a rear view of the carrier and conductor strips for connecting the coils in series.

This improved switch has a box or housing 1 which may be formed of metal or other suitable material. The box is mounted vertically upon a wall, instrument board, or other suitable support when in use and is open at its front, the open front of the housing or box being normally closed by a cover or door 2 which is normally held closed by latches 3 carried by the top and the bottom of the box. A pivot rod 4 extends transversely through the upper portion of the box or casing and upon this rod is tiltably mounted a block of insulation constituting the body of the switch. This body or block is arcuate longitudinally, as shown in Figure 1, and is formed in its front or outer face with a pocket 6 which occupies the major portion of its length and width but is spaced a greater distance from its upper end than its lower end in order to provide the block with a shoulder 7 across the upper end of the pocket.

A combined stationary contact and resistance is mounted in the pocket 6 and consists of a mounting sheet 8 which is formed of flexible insulating material and carries a plurality of resistance coils 9 connected by strips 10 of conductive material. The resistance coils and the connecting strips extend diagonally across the mounting sheet, as shown in Figures 6 and 7, with the coils bearing against the front face of the sheet and the strips bearing against the rear face thereof. Ends of the coils are connected with ends of the connecting strips by rivets 11 which pass through the side edge portions of the sheet. A terminal strip 12 of conductive material is secured across the lower end of the sheet by fasteners 13 and projects forwardly from the sheet and out of the pocket. The adjacent coil has its terminal portion 9' secured under the head of one rivet to establish electrical connection between the coil and the terminal strip, and midway its length the terminal strip is formed with an opening 14 which registers with an opening 15 formed through the block to receive a bolt 16. This bolt protrudes from the rear face of the block and in order that the bolt may have a screw driver applied to it the curved outer portion or lip of the terminal strip has a notch 17 formed in it. A conductor 18 extends longitudinally of the block, against the rear

face thereof, and at its lower end is formed with an opening through which the bolt passes so that this conductor will be firmly held against the block. The upper end of the conductor carries a screw 19 in order that a wire 20 may be connected with the conductor. After the sheet carrying the coils and the connecting strips has been fitted into the pocket and disposed against the bottom or inner wall thereof melted insulating material 21 is poured into the pocket about the coils and completely fills the pocket, but portions of the coils protrude from this insulating material. Therefore individual engagement may be made with the convolutions of the coils when the switch is closed, and since the coils extend diagonally in the pocket the resistance will have a long length relative to the length of the pocket.

The movable contact consists of a wide strip or sheet of flexible conductive metal 22 which is of greater length than the block and has its upper end secured flat upon the shoulder 8 by a suitable number of bolts 23 and its lower portion projecting downwardly from the block. One of the bolts has its threaded end portion passing through a conductor strip 24 which extends longitudinally of the block from the upper end thereof and at its lower end carries a terminal screw 25 to which a wire 26 is secured. When the block is in the position indicated by dotted lines in Figure 1 the movable contact strip or sheet will be out of engagement with the coils and a circuit through the switch will be broken. When the block returns to the position shown in full lines the movable contact sheet moves towards the block and progressively makes contact with the convolutions of the coils. This closes the circuit and as the convolutions of the coils are engaged the effective length of the resistance formed by the coils and the connecting strips is gradually reduced. Therefore the switch serves as a switch and also as a variable resistance.

The wire 26 is connected with a screw 27 carried by a terminal bracket 28 mounted upon the rear wall of the box 1 and to this screw is also connected the circuit wire 29. The wire 20 is connected with a screw 30 carried by a conductor strip 31 which is mounted in insulated relation to the rear wall of the box and secured by rivets 32. This conductor strip projects outwardly from the box through an opening in a side wall thereof and at its outer end carries a screw 33 to which a circuit wire 34 is connected. Current may therefore be supplied through the switch from a source of electric energy to an electrically operated device and by properly adjusting the position of the block the switch may be closed and the extent to which the movable contact engages the resistance coils controlled.

A spring 35 urges the block 5 towards the closed position. This spring has one end engaged with a hook 36 carried by the block midway the width thereof and its other end anchored to an arm or clip 37 projecting from a carrier 38 which is slidably mounted between tracks 39 for movement vertically along the rear wall of the box to adjusted positions. An eye 40 projects from the upper end of the carrier strip 38 and through this eye is swiveled the reduced end of a rod 41 which extends vertically in the box and has its upper end portion thickened and threaded. The threaded end portion of the rod passes through a threaded opening formed in the top wall of the box and its outer end is formed with a groove 42 to receive a screw driver by means of which the rod is turned to effect inward or out-

ward movement of the rod and thus shift the carrier 38 to adjusted positions where it is held by action of a locking nut 43. When this nut is tightened the rod will be held against turning and the carrier will be held stationary with the spring 35 under sufficient tension to urge the block 5 towards the position shown in full lines in Figure 1 and causing closing of the switch.

The movable contact strip or sheet 22 extends an appreciable distance beyond the lower end of the block 5 and passes across a roller 43 which is rotatably mounted upon a rod 44 extending transversely of the box. At its lower end the movable contact sheet is secured to a coupling 45 projecting upwardly from the core 46 of a solenoid 47 which rests upon the bottom of the box and has its mounting brackets 48 and 49 secured against the rear wall and the bottom of the box by screws 50 and 51. Terminal wires 52 and 53 of the solenoid are engaged with screws 54 and 55 carried by mountings 56 and 57 which are attached to the rear wall of the box in insulated relation thereto. When current is allowed to flow through the solenoid winding the core 46 is drawn downwardly and pull exerted upon the movable contact strip, thus causing the block 5 to be tilted about the rod 11 and towards the dotted lined position shown in Figure 1 and open the switch. A pin 58 projects from a side of the core and through a slot formed longitudinally of the cover or door 2, the pin being of such length that its protruding end portion may be readily gripped and the switch manually opened or closed when so desired. A latch 59 is pivoted to the outer surface of the door at one side of the slot for engagement with the pin to releasably hold the pin and the core against upward movement and thus prevent accidental closing of the switch.

Having thus described the invention, what is claimed is:

1. A switch comprising a casing, a block of insulation in said casing pivotally mounted for tilting movement, a fixed contact carried by said block and constituting a resistance having transversely spaced coils connected in series with each other and extending transversely across the block diagonally thereof, a movable contact consisting of a sheet of flexible conductive metal, said movable contact extending longitudinally of the block and having one end secured to an end of the block and its outer end portion free from the other end of the block, means for exerting longitudinal pull upon the movable contact and thereby tilting the block to an adjusted position and progressively moving the movable contact out of engagement with the coils of the resistance, and a spring yieldably holding the block against tilting movement and in its normal position with the movable contact in engagement with the resistance.

2. A switch comprising a casing, a block of insulation in said casing pivotally mounted for tilting movement, a fixed contact carried by said block and constituting a resistance, a movable contact carried by the block and consisting of a strip of flexible sheet metal extending longitudinally of the block with one end secured to one end of the block and its other end portion projecting from the other end of the block, a solenoid in the casing having its core connected with the outer end of the movable contact, the solenoid when energized exerting pull upon the movable contact and tilting the block towards a position disposing the movable contact out of

engagement with the resistance, a pin projecting laterally from the core and through a slot in the casing, a latch for engaging the protruding portion of the pin and releasably securing the movable contact and the block in an adjusted position, and spring means for tilting the block towards its initial position when the solenoid is de-energized.

3. A switch comprising a casing, a block of insulation in said casing pivotally mounted for tilting movement, a fixed contact carried by said block and constituting a resistance, a movable contact carried by the block and consisting of a strip of flexible sheet metal extending longitudinally of the block with one end secured to one end of the block and its other end portion projecting from the other end of the block, a solenoid in the casing having its core connected with the outer end of the movable contact, the solenoid when energized exerting pull upon the movable contact and tilting the block towards a position disposing the movable contact out of engagement with the resistance, a track in the casing extending longitudinally therein, an anchor shiftable longitudinally of the track, a spring having one end connected with the anchor and its other end connected with the block and exerting pull to tilt the block towards its normal position with the movable contact in engagement with the stationary contact, and a screw connected with the anchor for shifting the anchor along the track to adjusted positions.

4. A switch comprising a casing, a block of insulation disposed vertically in said casing and pivotally mounted for forward and rearward tilting movement, a fixed contact carried by said block and constituting a resistance having portions extending diagonally across the front of the block and connected in series with each other, a movable contact formed of flexible conductive metal and extending longitudinally of said block, along the front face thereof, with its upper end secured to the upper end of the block and its lower end free from the block, a spring having one end connected with the block above its pivot, an anchor for the other end of said spring shiftable vertically in the casing for placing the spring under desired tension and causing the spring to urge the block towards a tilted position disposing the movable contact in engagement with the resistance, and means for exerting downward pull upon the lower end of the movable contact and thereby tilting the block and progressively moving the movable contact out of engagement with the resistance.

5. A switch comprising a casing, a block of insulation disposed vertically in said casing and

pivottally mounted for forward and rearward tilting movement, a fixed contact carried by said block and constituting a resistance having portions extending diagonally across the front of the block and connected in series with each other, a movable contact formed of flexible conductive metal and extending longitudinally of said block along the front face thereof with its upper end secured to the upper end of the block and its lower end free from the block, means for exerting pull upon the movable contact and tilting the block to progressively move the movable contact away from the resistance, a spring back of said block having its upper end connected with the block above the pivot for the block, and means for anchoring the lower end of the spring and adjusting the tension thereof to cause the spring to urge the block towards a position separating the movable contact from the resistance.

20 6. A switch comprising a casing, a block of insulation disposed vertically in said casing and pivotally mounted for forward and rearward tilting movement, a fixed contact carried by said block and constituting a resistance having portions extending diagonally across the front of the block and connected in series with each other, a movable contact formed of flexible conductive metal and extending longitudinally of said block along the front face thereof with its upper end secured to the upper end of the block and its lower end free from the block, means for exerting pull upon the movable contact and tilting the block to progressively move the movable contact away from the resistance, a spring back of said block having its upper end connected with the block above the pivot for the block, a mounting carried by the rear wall of the casing and slidable vertically, the lower end of said spring being connected with said mounting, and a rod threaded 35 through the top of the casing and having its lower end swiveled to said mounting whereby turning of the rod will shift the mounting vertically and thereby apply desired tension to the spring and cause the spring to urge the block towards a tilted 40 position for gradually separating the movable contact from the resistance.
